UNITED STATES PATENT OFFICE

93,176

DESIGN FOR A CORSAGE PIN

Charles Murray, New York, N. Y.

Application June 4, 1934, Serial No. 52,062

Term of patent 14 years

To all whom it may concern:

Be it known that I, CHARLES MURRAY, a citizen of the United States, residing at New York, in the county of New York and State of New York, have invented a new, original, and ornamental Design for a Corsage Pin, of which the following is a specification, reference being had to the accompanying drawing, forming part thereof.

I claim:

The ornamental design for a corsage pin, as shown.

CHARLES MURRAY.
